CLAIM

The ornamental design for a neck towel, as shown and described.

DESCRIPTION

FIG. 1 is a bottom plan view of a neck towel showing my new design;

FIG. 2 is a side elevational view thereof, the opposite side being a mirror image of that shown;

FIG. 3 is an end elevational view thereof; and

FIG. 4 is a top perspective view thereof.

The cross-hatching is intended to represent conventional towel fabric and is understood to extend uniformly across the surfaces represented.
